[57] ABSTRACT

A watchband or the like including special clips secured to the band for gripping and retaining the watch on the band. Each of the clips includes, at one end, a resilient reverted loop which receives one of the mounting pins on the watch case. The clips are secured at their other ends to the watchband by offset mounting tabs which pass through slots in the band. The offset tabs are secured to the underside of the band by a rivet which passes both through the band and the offset tab.

WATCHBAND

BACKGROUND OF THE INVENTION

This invention relates to watchbands or the like and, more particularly, to an improved watchband which enables a conventional wristwatch to be secured and attached thereto quickly and simply yet which retains the attached watch firmly. Unlike many conventional watchbands the watch, having generally parallel attaching pins located at opposite ends of the watch case, may be attached to the watchband simply by slipping each of the attaching pins into a specially formed clip which, in turn, is secured to the watchband. The attaching pins need not be separated from the watch case and, therefore, the usual difficult manipulations required to detach and reassemble the attaching pins is avoided. Although other arrangements have been proposed in the prior art to fasten the attaching pins to the watchband without requiring that the pins be removed from the watch casing, these arrangements generally have included fasteners which must be arranged and locked by the user. The further manipulative steps required in such watchbands are avoided with the instant invention which includes self-locking and retaining clips of a special design.

A further difficulty encountered with prior watchbands which may be attached to the attaching pins without requiring removal of the attaching pins from the watch case is that the connective elements frequently are formed from thin leather or other flexible but tearable material. Because of the relatively weak construction of these connecting elements there is a correspondingly greater chance that the connecting elements may break or tear with the result that the watch may become separated from the watchband and may become damaged. Additionally, in watchbands having conventional snap-type connective fittings the snaps open inadvertently, particularly when the watch is used in a rough environment. Obviously, such inadvertent release of the watch may result in considerable damage to the watch.

Finally, a number of such watchbands include connective fittings which may tend to open as a result of the stresses imposed on the fittings as the watchband is wrapped about the user's wrist. In contrast, the watchband of the instant invention results in a more effective grip on the watch as it is wrapped about the user's wrist.

SUMMARY OF THE INVENTION

In brief, the invention includes a watchband having a pair of specially formed resilient clips fastened thereto. The clips are spaced along the watchband to receive the watch case therebetween. The clips include a special reverted resilient loop into which the attaching pins of the watch case may be snapped. Once the pins have been snapped into the resilient loops they are retained therein firmly at all times. Each clip includes one such loop for engagement with one of the two attaching pins on the watch case. Each clip also includes an offset mounting tab at the end opposite the reverted loop. The offset tab passes through a transverse slot formed on the watchband so that the tab is disposed along the underside of the band. The clip is secured to the watchband by means of a rivet which passes through the band and the offset tab with the head of the rivet exposed at the outer surface of the band in proximity to the exposed portion of its associated clip.

It is among the objects of my invention to provide a watchband which grips positively the attaching pins of a watch case and which enables the watch and watchband to be assembled without requiring removal of the attaching pins from the watch case.

A further object of my invention is to provide a watchband of the character described which has few elements and is of simple, economical construction.

Yet another object of the invention is to provide a watchband of the character described having resilient snap-in clips which receive the attaching pins of the watch case in a snap-in fashion and which thereafter maintain a secure and firm grip on the attaching pins.

A further object of the invention is to provide a watchband construction in which the attaching clips of the watch are anchored firmly and securely to the watchband but which do not impair the flexibility of the watchband.

Still another object of the invention is to provide a watchband which increases its grip on the watch when the watchband is wrapped about the user's wrist.

DESCRIPTION OF THE DRAWINGS

Other objects and advantages of the invention will be apparent from the following detailed description thereof with reference to the accompanying drawings wherein:

FIG. 1 is a plan view of a watchband construction in accordance with the invention;

FIG. 2 is a sectional view taken through the clip as viewed along the line 2-2 of FIG. 1; and

FIG. 3 is an illustration of a blank from which the clip may be formed.

As shown in FIG. 1 the invention includes a watchband or base member 10 of flexible material such as leather, plastic, flexible metal or other material suitable for use as a watchband. Conventional means such as a buckle 12 and a number of holes 14 are located at opposite ends of the watchband 10 to enable it to be fastened, about the user's wrist.

The watch 16, shown in phantom, is mounted to the outer surface 18 of the basemember 10 by means of specially constructed clips, indicated generally by the reference character 20. The clips 20 are spaced along the base member 10 to embrace the ends of the watch 16. The clips 20 are of a special construction to receive the attaching pins 22 of the watch case in a snap-on fashion without requiring removal of the pins 22 from their respective sockets formed in lugs 24 which protrude from the corners of the watch 16.

The clips may be formed from a blank as shown in FIG. 3, which has a hole 26 formed through one end for a purpose later described. As shown in FIG. 2, each clip 20 includes an offset mounting tab 28 formed at the end of the clip 20 which includes the hole 26. In the illustrative embodiment of the invention the offset tab 28 is arranged in generally parallel relation to the body 30 of the clip, the tab 28 and body 30 being connected by an integral connective portion 32. The other end of the clip 20 is bent into a reverted loop 34, the free end of which cooperates with the underside of the body 30 of the clip 20 to define a restricted opening or mouth 36. The extreme end of the loop 34 is curled in reversed direction to define a curled lip 38 which serves to facilitate entry through the mouth 36 into the reverted loop 34. The end of the curled lip 38 should be spaced from the connective portion 32 to enable the

attaching pin 22 of the watch to be passed therebetween and through the mouth 36 into the loop 34.

The clip 20 preferably is formed from spring brass or other resilient metal which may be bent easily into the desired configuration and still retain its resilience. The mouth 36 is smaller in width than the diameter of the attaching pin so that when the pin is snapped through the mouth and into the loop it will be retained resiliently therein. The clearance between the edge of the curled lip and connective portion 32, however, preferably is larger than the diameter of the attaching pin 22 so that the pin 22 may be aligned easily with the mouth 36 in readiness to be snapped into the loop 34.

The clips 20 are attached to the watchband 10 by means of transverse slots 40 formed in the watchband 10. The offset mounting tabs 28 are passed through the slots 40 so that the tab 28 is in engagement with the lower surface 42 of the band while the remaining portion of the clip 20, including the reverted loop 34, is disposed along the outer surface 18 of the band 10. In the preferred embodiment of the invention the clips 20 are secured to the base 10 by rivets 44 which pass through the base 10 and hole 26 formed in the offset mounting tab 28. It is preferred to insert the rivets so that their heads 46 are exposed at the outer surface 18 of the base 10 in proximity to the clip 20. The rivet heads 46, which preferably are formed from the same material as the clips 20, provide an aesthetically pleasing arrangement along the outer surface 18 of the watchband.

Thus, each clip 20, is attached firmly to the base 10 by the rivet 44 and is maintained in place by the engagement of the connective portion 32 with the slot 40 formed in the base 10.

The clips are arranged so that when they are fastened to the watchband their reverted loops 34 open in opposite directions. When attaching a watch to the watchband, the base may be folded over to expose clearly the underside of the clip and the restricted mouth 36. One of the attaching pins 22 of the watch case then is slipped between the curled lip 38 and the connective portion 32 and then is snapped through the restrictive mouth 36. Once the attaching pin is disposed within the loop, the resilient loop snaps back to its original position, with the loop being wrapped about its associated attaching pin 22 thus retaining the attaching pin firmly. It is unnecessary to remove the attaching pin 22 from engagement with the lugs 24 of the watch case at any time. The other attaching pin then is inserted into the reverted loop 34 of the other clip 20 in the same manner.

As shown in FIG. 2, it may be desirable to form the clip 20 so that the heightwide space between the tab 28 and the bottom region of the loop 34 is somewhat less than the thickness of the watchband 10. This requires that the watchband be bent downwardly slightly as shown in FIG. 2 in a curve which tends to follow the contour of the user's wrist. With this modification the clip 20 tends to remain closely to the watchband 10 when it is worn and, therefore, tends to hold the watch 16 firmly against the watchband and avoids any tendency of the watch 16 to lift up and away from the watchband 10.

Once the watch has been attached to the band it can be removed only by deliberate separation of the attaching pins 22 from the reverted loop 34. There is virtually no likelihood that the attaching pin may separate inad-

vertently from its associated reverted loop 34. Because the clips 20 are of unitary construction and do not include separate connectable or disconnectable fasteners, the likelihood of accidental separation of the watch 16 from the band is minimized further.

Thus I have provided an improved watchband which insures a firm grip on the watch yet which is of simple and economical construction as well as being aesthetically pleasing. The watch may be attached quickly and simply with minimum manipulation. Additionally, because mounting of the clip to the watchband the watch cannot slip about on the watchband.

It should be understood that the foregoing description is intended merely to be illustrative of my invention and that other embodiments and modifications will be apparent to those skilled in the art without departing from its spirit. For example, although the invention has been described as used in a watchband adapted to be fastened to the user's wrist, it may be employed to secure watches to other base elements or members such as fobs, pins, pendants, or the like.

Having thus described my invention what I desire to claim and secure by Letters Patent is:

1. A device for holding a watch having attaching pins located at the opposite ends of the watch comprising: a flexible base member adapted to encircle one's wrist; a pair of clips secured to said base member, said clips being spaced to receive said watch therebetween; each of said clips being of resilient construction and having a reverted loop formed thereon, each of said loops being disposed on the same side of said base member as said watch and being positioned along said base member to receive the attaching pins of said watch, each of said loops opening in a direction that is away from the other of said clips and away from the position at which said watch is supported; each of said loops defining an opening which is restricted to present a yieldable obstruction to the passage of said attaching pins through said opening, whereby said attaching pins may be snapped into said loop and be retained within said loop; said free end of said reverted loop having a reverse curl to that of said reverted loop and the terminating end is disposed along the outer surface of said flexible base member when said base member is wrapped about one's wrist; said reverse curled portion being effective to facilitate initial engagement of said attaching pin with the mouth of said loop and to guide said attaching pin into said loop as said pin and loop are snapped together; said clip including an offset integral mounting tab formed at the end opposite said reverted loop, said tab being offset by a connective portion of said clip, said connective portion and said flared end of said loop defining a passage of greater dimensions than the diameter of said pin of said watch to enable said pin to pass freely therethrough; said base member having a slot formed therethrough for reception of said connective member to enable said tab to be located on the underside of said base member; and means for securing said offset tab portion of said clip to said base member.
2. A device as defined in claim 1 further comprising:

said base member being of a predetermined thickness; and
the height-wise dimension between said tab and the
lower portion of said loop being slightly less than
said predetermined thickness of said base member 5

whereby when said base member is wrapped about
one's wrist the watch will be held firmly against the
watchband and will avoid a tendency of the watch
to lift up and away from the watchband.
